UNITED STATES PATENT OFFICE.

JAMES H. MATHESON, OF WYOMISSING, PENNSYLVANIA, ASSIGNOR TO DONALD E. MATHESON, OF EDGEWOOD, PENNSYLVANIA.

APPARATUS FOR MAKING LAP-WELDED TUBES.

Application filed July 28, 1926. Serial No. 125,474.

One object of my invention is to improve the construction of apparatus for making lap welded tubes, so that a tube can be completely formed directly from the flat blank 5 in a continuous operation.

A further object of the invention is to so construct the apparatus that its capacity is greatly increased, and if there is a breakdown at any one point, it will not interfere 10 with the continuous operation of the apparatus.

In the accompanying drawings:

Fig. 1 is a plan view of my improved apparatus shown in diagram, the two furnaces being in section;

Fig. 2 is a side view showing the two furnaces in section;

Fig. 3 is a transverse sectional view on the line 3—3, Fig. 1;

Fig. 4 is a transverse sectional view on the line 4—4, Fig. 1;

Fig. 5 is a transverse sectional view on the line 5—5, Fig. 1; and

Fig. 6 is a side view of one of the sizing rolls.

1—1 are the tables, on which are located the flat blanks or skelps *a* from which the tubes are to be formed. 2—2 are pushers of the ordinary type for moving the blanks into and out of the furnace 3. The blanks *a* are heated in this furnace before bending. These blanks *a* are arranged side by side and are brought into alignment with the scarfing rolls 4, which latter rolls scarf the edges of the blanks *a* as they are passed between them. The blanks, after passing through the scarfing rolls 4, are discharged onto a roller table 5. The rollers on this table are driven in the ordinary manner and 35 guide rails 6 form tapered ways to direct the scarfed blank to the bending dies 7.

In some instances, the scarfing rolls may be omitted or may be opened to allow the blanks to pass through the rolls without being scarfed by them, as in some instances the blanks or skelps are scarfed during the rolling process and come to the tube mill in a scarfed condition.

In the present instance, there are two hot 50 scarfing rolls located side by side and two bending dies. It will be understood that this machine is a "double machine", that is, two blanks are bent into tubes in one operation, the blanks traveling through the apparatus side by side, and the mechanism on

one side of the apparatus is a duplicate of that on the opposite side.

After the blanks are bent into tubular form, they are discharged onto a chain-table 8, located in line with the bending dies. 60 Rails 9 are located between each chain-table and a longitudinal roller trough 10, so that the bent blanks are moved laterally over the rails from the chain-tables to the troughs 10. Each trough 10 is pivotally mounted 65 so that it can be turned end for end when it is desired to reverse the tubular blank. Each trough 10 is in line with a longitudinal roller trough 12.

Inclined rails 13 (Fig. 4) are arranged 70 between the roller trough 12 and the troughs 14 in front of the openings 15 in the welding furnace 16. Pushers 17, mounted on overhead rails 18, push the tubular blank into the welding furnace 16, and when the 75 tubes have reached the welding heat, they are rolled into position to be pushed out of the furnace 16 and between the welding rolls 19. The welded tubes then pass onto troughs 20 and roll down the inclined rails 80 21 (Fig. 5) to side troughs 22.

The troughs 22 are in line with the sizing rollers 23, so that when the tubes are pushed from the troughs 22 they pass between the sizing rolls and into troughs 24, 85 and from these troughs the tubes are passed between the cross-rolls 25 and onto the receiving tables 26, from which they are transferred to the cooling chain-tables 27 at the discharge end of the apparatus. From 90 these tables the tubes may be passed through straightening rolls 28. The rod pullers are shown at 33. These pullers are used to pull the ball-rods 34 from the formed tubes.

If it is necessary to double weld the tubes, then the tubes are transferred from the troughs 20 onto a central trough 29, which is pivotally mounted on a piston 30 within a cylinder 31, so that the trough 29 can be raised clear of the other troughs and can be 100 turned by a rack-and-pinion, shown in diagram in Fig. 5.

After the welded tube has been located in the trough 29 and the trough turned so as to reverse the tube, the latter is again pushed into the welding furnace 16, and when at 105 welding heat is again passed between one of the sets of welding rolls. This double welding insures a perfect welding of the tubes.

By arranging the apparatus in the manner described, two complete sets of bending and welding units are provided, and consequently the capacity of the apparatus is greatly increased over the ordinary apparatus, as two bending rolls can be used with one welding roll, or one bending roll can be used with two welding rolls, and if there should be a break-down at any point, then the blanks can be fed around the break-down without interfering with the continuous production.

I claim:—

1. The combination in apparatus for making lap welded tubes, of a skelp heating furnace; scarfing rolls located in front of the furnace and arranged to scarf the blanks as they pass from the furnace; a table for receiving the scarfed blanks; a bending die through which the blanks travel; a support for receiving the bent blanks; means for allowing the blanks to move laterally into a pivoted trough; a longitudinal trough in line with the pivoted trough; means for carrying the blanks from said trough to a fixed trough in front of the welding furnace; a pusher for introducing the tubular blank into the furnace and for projecting a tubular blank therefrom; and welding rolls in front of the welding furnace between which the blank is passed and welded.

2. The combination in apparatus for making lap welded tubes, of a skelp heating furnace; a scarfing roll located in front of the furnace and arranged to scarf the flat blanks as they pass from the furnace; a table for receiving the scarfed blanks; a bending die through which the blanks travel; a support for receiving the bent blanks; means for allowing the blanks to move laterally into a pivoted trough; a trough in line with the pivoted trough; means for carrying the

blanks from said trough to a fixed trough in front of the welding furnace; a pusher for introducing the tubular blanks into the furnace and for projecting the tubular blanks therefrom; welding rolls in front of the welding furnace through which the blanks are passed and welded; means for allowing the blanks to move laterally after they have passed through the welding rolls; sizing rolls through which the blanks pass; and cross-rolls for straightening the blanks.

3. The combination in continuous apparatus for forming lap welded tubes, of a skelp heating furnace; means for feeding a skelp to the furnace; scarfing rolls at the front of the furnace; bending dies for bending the scarfed blanks into tubular form; a table for receiving the tubular blanks; rails for carrying the tubular blanks laterally to outside troughs; means for turning the troughs end for end; a welding furnace; means for positioning the blanks in front of the furnace; welding rolls at the opposite end of the furnace; and means for pushing the blanks from the furnace through the welding rolls.

4. The combination in apparatus for forming lap welded tubes, of a furnace for heating skelps; means for bending the scarfed skelps; means for turning the skelps end for end; a welding furnace into which the scarfed and bent blanks are inserted; welding rolls in front of the furnace through which the blanks are passed after being brought to welding heat; troughs for receiving the welded blanks; a central trough arranged to be turned end for end to allow the welded tube to be inserted into the welding furnace from the front end for the purpose of re-welding; sizing rolls; and cross-rolls through which the welded tubes pass.

JAMES H. MATHESON.
